ATTORNEYS

UNITED STATES PATENT OFFICE.

ABRAHAM SACKS, OF BROOKLYN, NEW YORK.

TASSEL.

Application filed July 15, 1926. Serial No. 122,640.

This invention relates to tassels, an object of the invention being to provide an ornamental and attractive tassel which can be manufactured and sold at an extremely low price and which dispenses altogether with the necessity for an inner core member or block at the head of the tassel.

With this and other objects in view, the invention consists in certain novel features of construction and combinations and arrangements of parts, which will be more fully hereinafter described and pointed out in the claim.

In the accompanying drawings—

Figure 1 is a view in elevation, illustrating my improved tassel, a portion being broken away to illustrate the detail of construction;

Figure 2 is a view in elevation, showing the manner of assembling the parts of a tassel;

Figure 3 is a view in transverse section on the line 3—3 of Figure 1;

Figure 4 is a view in transverse section on the line 4—4 of Figure 2;

Figure 5 is a fragmentary perspective view, illustrating one of the strands of the spiral covering member which constitutes the head of the tassel.

1 represents the tassel cord, 2 what is commonly known in the trade as the bunch, and 3 my improved spiral clamping head. The spiral clamping head 3 comprises a coiled strand, such as illustrated in Figure 5, which consists of an inner spring wire 4 and an outer covering 5 of silk, satin or any other suitable ornamental material. This strand is wound in spiral form and constitutes to a certain degree a spiral spring. It is smallest at its upper end, as shown at 6, for the passage of a double run of the cord 1. Furthermore, this coiled head 3 reduces in diameter toward its lower end, or, in other words, it tapers slightly, as clearly indicated in Figure 2.

In constructing the tassel, the cord is looped or folded upon itself, and the material or threads forming the bunch 2 are projected through the looped portion of the cord so that the intermediate portions of 50 the strands of the bunch are supported on the cord. The coiled head 3 is then forced downwardly over the looped portion of the cord and over the intermediate portions of the strands forming the bunch 2, securely 55 clamping the intermediate strands of the bunch and forming a complete tassel, as indicated in Figure 1.

The grip of the spirally wound head 3 is sufficient to hold the latter in place, and, 60 in fact, maintain all parts of the tassel assembled, but, if it is desired, the cord or strand may be knotted above the head 3 although this is by no means essential to my invention.

Various slight changes and alterations might be made in the general form of the parts described without departing from my invention and hence I do not limit myself to the precise details set forth but consider 70 myself at liberty to make such slight changes and alterations as fairly fall within the spirit and scope of the appended claim.

I claim:

A tassel of the character described, comprising a cord having a loop therein, strands projecting through the loop and constituting a bunch, and a spirally wound resilient head movable on the cord and adapted to be forced over the looped portion of the 80 cord and the bunch and constituting an enclosure for said looped portion of the cord and the upper portion of the bunch, said spirally wound head being of normally less diameter at its lower portion than at its 85 intermediate portion whereby the head grips the bunch by its inherent resiliency and maintains itself in place on the bunch.
